UNITED STATES PATENT OFFICE

HAROLD E. JOHNS, OF LANSDOWNE, PENNSYLVANIA, ASSIGNOR TO COVER & COMPANY, OF PHILADELPHIA, PENNSYLVANIA, A PARTNERSHIP CONSISTING OF THOMAS COVER, JR., AND THOMAS C. BARTON, BOTH OF BRYN MAWR, PENNSYLVANIA, AND BERNARD J. SEGUT, OF MERION, PENNSYLVANIA, AND HIMSELF

LEATHER-SORTING MACHINE

Application filed June 29, 1929. Serial No. 374,875.

This invention relates to sorting machines and, more particularly, to a machine for sorting leather sole blanks of the type now in common use.

As is well known to those familiar with the art, the thickness of sole leather in such blanks varies considerably, depending upon the portion of the hide from which the blank is formed and the present practice is to employ a gauge having an angular notch in which the edge of the blank is inserted to determine the thickness. Obviously, blanks employed upon a pair of shoes must be of the same thickness and this sorting is further necessary due to the fact that blanks of different thicknesses naturally have different weights and accordingly must be sold for different prices. An important object of the present invention is the provision of a structure for automatically sorting such blanks and delivering them to receivers.

A further and more specific object of the invention is the provision of a thickness gauge having a longitudinally-extending slot varying in width from end to end, having associated therewith a means for causing the blanks to travel therewith, the blank passing through the gauge when it arrives at a point such that its size permits it to do so.

A further object of the invention is the provision of a construction such that the blank, once it begins its passage through the thickness gauge, is rapidly drawn therethrough so that there is no danger of its being shifted by the conveying mechanism to a point where it will enter a receiver other than that in which it belongs.

A still further object of the invention is to provide, in apparatus of this character, a gauge construction eliminating, in so far as possible, the resistance to the passage of the blank resulting from friction as the blank is moved therewith.

These and other objects, I attain by the construction shown in the accompanying drawings wherein, for the purpose of illustration, I have shown a preferred embodiment of my invention and wherein:

Fig. 1 is a front elevation of a sorting ma-

chine constructed in accordance with my invention:

Fig. 2 is an end elevation thereof;

Fig. 3 is a section on line 3-3 of Fig. 1; and

Fig. 4 is a section on line 4-4 of Fig. 1.

Referring now more particularly to the drawings, numerals 10 and 11 designate spaced supporting standards. Journalized in the standards 10 and 11 adjacent the upper ends thereof are upper and lower pairs of rollers 12 and 13. Rollers 12 are constructed and arranged to provide therebetween a gap 14 which increases in width from end to end of the rollers. This gap may be produced either by mounting the rollers with their axes diverging or by tapering the rollers longitudinally. Rollers 13 may have their axes parallel and may afford therebetween a gap 15 which is uniform in width, although it is preferred, as in the case of the rollers 12, that it increase in width. The gap 15, however, will be of less width at any given point than the gap 14 at the same point.

Arranged above the rollers 12 and 13 and supported from standards 10 and 11 are vertically-spaced pairs of guides 16 and 17, these guides aligning with the gap between the rollers in such fashion that a blank 18 disposed therebetween is guided into the space between rollers 12 and is aligned with the space between rollers 13. The guides 16 and 17 are connected at spaced intervals by vertically-extending standards 19 which, at one side of the guiding structure thus produced, may be offset outwardly, as at 20, to provide seats for a guide rail 21 in the form of an angle iron. The horizontal flange 22 of this iron supports one run of a conveyor chain 23, which run at its ends is directed about sprocket wheels 24 and 24^a mounted in vertically-extending bearings carried by the standards 10 and 11. The sprocket wheel 24 is secured to a shaft upon the lower end of which is mounted a bevelled gear 25.

Associated with the standard 10 is a driving motor 26 which, through suitable gearing, operates a main driving gear 27. The driving gear 27 is located within a gear case 28 carried by the upper end of standard 10.

and meshes with a gear 29 secured to the end of one of the rollers 12. The other of the rollers 12 has secured thereto a gear 30 meshing with gear 29 and with a gear 31 upon the end of the roller 13 lying therebelow. Rollers 13 inwardly of standard 10 are provided with meshing gears 32. It will be obvious that on the rotation of gear 27, rollers 12 will rotate in opposite direction and rollers 10 13 will rotate in opposite directions, and the rotation of corresponding rollers 12 and 13 will be opposed. The direction of rotation is such that adjacent faces of rollers 12 are moved upwardly, while those of rollers 13 are moved downwardly.

15 The gear 29 also meshes with a gear 33 secured to one end of a shaft 34 extending through the standard and having at its inner end a bevelled gear 35 meshing with the bevelled gear 25 of the conveying sprocket shaft. The conveyor chain is provided with spaced projecting flight elements 36 to engage against the sole blanks 18 as they are placed between the guides 16 and 17. A 20 rack or supporting magazine 37 is conveniently secured to the upper end of standard 10 through an arm 38.

In use of the apparatus, it will be obvious that as the blanks are drawn along the rollers 12, in alignment with the slot 14 thereof at the narrow end of the slot and cause them to travel along this slot, they will, upon arrival at a point where the width of the slot is greater than their thickness, pass 30 through this slot and thus come into engagement with rollers 13 which will grip the blank and cause it to be discharged downwardly. To assist in this gripping action, the faces of rollers 13 are preferably covered 35 with friction material, as indicated at 39, and this material is preferably of such a nature that it is resilient. Rubber may be conveniently employed.

The standards 10 and 11 are preferably 40 employed to support receivers 40, these receivers being at present illustrated in the form of chutes adapted to discharge into movable bins generally designated in dotted lines in Fig. 1. In order that these bins 45 may be made of sufficient size to hold a reasonable quantity of blanks and, at the same time, adequate space may be provided therefor, alternate chutes 41 preferably discharge in opposite directions, as indicated. It will, 50 of course, be obvious that this arrangement is entirely arbitrary and that other means for taking care of the sorted blanks than that shown may be employed.

55 Attention is directed to the fact that since adjacent faces of rollers 12 are moving upwardly, they will tend to elevate the blanks 18 with the result that the blanks will have no tendency to wedge in the slot as would ordinarily be the case were a slot employed

having a tapered mouth, such as is afforded by the rollers.

Since the construction illustrated is capable of a very considerable change and modification without in any manner departing 70 from the spirit of my invention, I do not wish to limit myself to the specific structure illustrated except as hereinafter claimed.

I claim:

1. In sorting apparatus, means providing 75 a tapering slot varying in width from end to end, a series of receivers arranged therebeneath, means for causing articles to shift longitudinally of the slot until their arrival at a point where they may pass therethrough, 80 and means engaging an article after a predetermined portion thereof has passed through the slot and discharging the same to the underlying receiver.

2. In sorting apparatus, means providing 85 a tapering slot varying in width from end to end, a series of receivers arranged therebeneath, means for causing articles to shift longitudinally of the slot until their arrival at a point where they may pass therethrough, 90 means engaging an article after a predetermined portion thereof has passed through the slot and discharging the same to the underlying receiver, and means guiding the article during its travel along the 95 slot maintaining the same in alignment with the slot and said engaging means.

3. In apparatus for sorting flat articles in accordance with their thickness, means providing a gauging slot varying in width 100 from end to end, a series of receivers arranged therebeneath, means for causing edgewise travel of the article longitudinally of the slot until its arrival at a point where it may pass therethrough, and means engag- 105 ing the article after a predetermined portion thereof has passed through the slot and discharging the same to the underlying receiver.

4. In apparatus for sorting flat articles in 110 accordance with their thickness, means providing a gauging slot varying in width from end to end, a series of receivers arranged therebeneath, means for causing edgewise travel of the article longitudinally of the slot until its arrival at a point where it may pass therethrough, and rotatable rollers arranged 115 between the slot and said receivers for gripping an article after a predetermined portion thereof has passed through the slot and discharging the same to the receiver.

5. In apparatus for sorting flat articles in accordance with their thickness, means providing a gauging slot varying in width from end to end, a series of receivers arranged therebeneath, means for causing edgewise travel of the article longitudinally of the slot until its arrival at a point where it may pass therethrough, and rotatable rollers arranged 120 between the slot and said receivers for grip- 125 130

ping an article after a predetermined portion thereof has passed through the slot and discharging the same to the receiver, said rollers having faces of friction material.

5 6. In apparatus for sorting flat articles in accordance with their thickness, means providing a gauging slot varying in width from end to end, a series of receivers arranged therebeneath, means for causing edgewise 10 travel of the article longitudinally of the slot until its arrival at a point where it may pass therethrough, and rotatable rollers arranged between the slot and said receivers for gripping an article after a predetermined portion 15 thereof has passed through the slot and discharging the same to the receiver, said rollers being faced with elastic friction material.

7. In a sorting machine, a pair of rollers combining to produce a slot varying in width 20 from end to end, conveyor means for shifting articles engaging said rollers along the same, means for rotating said rollers to cause adjacent faces to move toward articles supported thereby, and gripping means arranged 25 beneath said rollers and engaging an article after partial projection thereof through the slot to complete the passage of the article.

8. In a sorting machine, upper and lower pairs of rollers, the rollers of each pair affording a slot therebetween, the slot between the upper rollers varying in width from end to end, means for rotating the rollers of each pair and corresponding rollers of the pairs in opposite directions, means for maintaining 35 the articles to be sorted in alignment with the slots between the rollers, and means for shifting articles to be sorted longitudinally of said rollers.

9. In a sorting machine, upper and lower 40 pairs of rollers, the rollers of each pair affording a slot therebetween, the slot between the upper rollers varying in width from end to end, means for rotating the rollers of each pair and corresponding rollers of the pairs in opposite directions, and means for shifting articles to be sorted longitudinally of the upper pair of rollers in contact therewith.

10. In a sorting machine, upper and lower pairs of rollers, the rollers of each pair affording a slot therebetween, the slot between the upper rollers varying in width from end to end, means for rotating the rollers of each pair and corresponding rollers of the pairs in opposite directions, means for shifting 55 articles to be sorted longitudinally of the upper pair of rollers in contact therewith, and a series of receivers beneath said rollers and into which articles are discharged by the lower pair of rollers.

60 11. In a sorting machine, upper and lower pairs of rollers, the rollers of each pair affording a slot therebetween, the slot between the upper rollers varying in width from end to end, means for rotating the rollers of each 65 pair and corresponding rollers of the pairs in

opposite directions, and means for shifting articles to be sorted longitudinally of the upper pair of rollers in contact therewith, the lower pair of rollers having friction surfaces.

70 12. In a sorting machine, upper and lower pairs of rollers, the rollers of each pair affording a slot therebetween, the slot between the upper rollers varying in width from end to end, means for rotating the rollers of each pair and corresponding rollers of the pairs in opposite directions, and means for shifting 75 articles to be sorted longitudinally of the upper pair of rollers in contact therewith, the lower pair of rollers having faces of elastic friction material.
